UNITED STATES PATENT OFFICE.

FREDERICK M. STEVENS, OF NEW YORK, N. Y., ASSIGNOR TO JOHN CHATILLON & SONS,
A CORPORATION OF NEW YORK.

METHOD AND APPARATUS FOR WIRING COIL-SPRINGS.

1,351,448.

Specification of Letters Patent. Patented Aug. 31, 1920.

Application filed November 13, 1917. Serial No. 201,768.

To all whom it may concern:

Be it known that I, FREDERICK M. STEVENS, a citizen of the United States, and residing at New York city, county of New York, and 5 State of New York, have invented certain new and useful Improvements in Methods and Apparatus for Wiring Coil-Springs, of which the following is a specification.

This invention relates to method and apparatus for wiring coil springs before tempering. Coil springs are used in large quantities for tire pressure gages, scales, etc., and it is necessary that such springs be of uniform strength. Heretofore, in order 10 to obtain uniformity of springs, it has been customary to wire them by hand before the springs are tempered, but such hand methods are slow and expensive and it is difficult to apply the binding wires by hand so as 15 to keep the springs of uniform shape and under uniform pressure. If one or more of the coils slip, the spring does not uniformly temper and may have to be rejected.

The present invention comprises a method 20 and apparatus for uniformly wiring such springs while holding the spring itself against distortion, and has the result of effecting a considerable saving in the cost of such work and also insuring greater uniformity of product.

In the accompanying drawings,

Figure 1 is an elevation of one form of apparatus for carrying out the invention,

Fig. 2 is an end view of a portion of 30 Fig. 1,

Fig. 3 is a sectional view of the mandrel and twisting head on an enlarged scale,

Fig. 4 is an end view of the mandrel, and

Fig. 5 is a view of a wire spring ready 40 for tempering or subsequent treatment.

1 represents a mandrel consisting of a hollow cylindrical body portion 2 having a central core 3, the core being spaced from the hollow body 2 so as to form an annular 45 space of substantially the size of the spring coil and receiving the coil. The function of this is to hold the coils against displacement or distortion, since the coils in springs of this character are easily displaced. The 50 body 2 and the core 3 are provided with parallel slots 4, 5 to receive a looped wire 6, the function of the slots being to prevent the wire from being turned when the projecting ends 7 are twisted together as shown

in Fig. 5. The procedure is to place one or 55 more previously prepared looped or doubled wires 6 in the mandrel slots, then insert the coil spring 8, and finally twist the ends 7 together. The end of the core 3 is provided with a slot or index 9 for the purpose 60 of positioning the end of the coil 10 in fixed relation to the wires 6, so as to insure absolute uniformity of the springs. If this is not done, there is a tendency for the 65 springs to vary owing to the difference caused by applying the wires at different points, and also because one wire should be applied at or near the end of the coil.

The wires are twisted by means of a rotating head 12 having a slot 13 for receiving the wire ends 7 and a twisting pin 14. The head 12 is mounted on a shaft 15 which is journaled in a frame 16 and operated by a crank 17. The mandrel is supported on a rest 18 having guide pins 19 and an end stop 20 engaging the end of the mandrel. The shaft 15 is mounted to reciprocate from the extreme left position as shown in Fig. 1 toward the right sufficiently for the head 12 to clear the ends of the wires, and to 80 enable this to be readily accomplished, the shaft is provided with a wing 21 which is loosely engaged in a slot in the crank arm 17. The crank arm is held in position on the shaft by means of pins 22 on opposite 85 sides thereof, while the crank arm is extended and provided with a hook 23 which engages a fixed disk 24 mounted on the frame 16.

By this construction, the shaft 15 can be 90 reciprocated back and forth in the frame 16 by a corresponding movement of the handle 25, while whenever the handle 25 and the crank arm 17 are rotated, the shaft 15 is turned through the wing 21. The loop 95 23 and the disk 24 cooperate to act as a fulcrum when the shaft is reciprocated, and also prevent disengagement when the shaft is turned.

After the springs and wires are assembled 100 in the mandrel, the operator simply has to place the mandrel on the support 18 against the stop 20 and then engage the twisting head 12 with the projecting wires 7 by manipulation of the crank arm 17 through 105 handle 25. Having effected the engagement the handle is then rotated to twist the wires.

What is claimed is:

1. The method which consists in tying the coils of a formed spring in contact with each other while holding the spring coils and tie against displacement with respect to each other and confining the spring in normal shape by a mandrel.
2. The method which consists in twisting a longitudinal wire tie at a predetermined position on the coils of a formed spring while holding the spring against lateral displacement by a mandrel confining the spring in normal shape.
3. The method which consists in placing a plurality of loops of wire and a formed coil spring on a mandrel and then fastening the ends of the wire to hold the spring under uniform compression in its predetermined form.
4. The method which consists in positioning a loop of wire on a mandrel, positioning a coil spring on the mandrel so as to be held in shape by the mandrel and embraced by the loop, and then fastening the ends of the loop to hold the spring to its predetermined form.
5. The method which consists in placing a plurality of loops of wire and a formed coil spring on a cylindrical mandrel so as to hold the spring in shape and the loops in predetermined relation, and then twisting the ends of the loops to compress the coils of the spring in contact with each other.
6. A mandrel for wiring a formed coil spring comprising a portion formed to fit the spring and adapted to receive and hold a wire loop on opposite sides of the coil against turning.
7. A mandrel for wiring a formed coil spring comprising a portion formed to closely fit the spring and having means adapted to receive and hold a wire loop on opposite sides of the coil against turning.
8. A mandrel for wiring a formed coil spring comprising a portion formed to fit the spring and adapted to receive and hold a wire loop on opposite sides of the coil against turning, and an index for determin-
- ing the relative position of the coil end and the wire loop.
9. A mandrel for wiring a formed coil spring comprising a hollow cylinder having an interior core providing an annular space to receive a coil spring, and means for receiving and holding a wire loop on opposite sides of the spring coils.
10. A mandrel for wiring a formed coil spring comprising a hollow cylinder having an interior core providing an annular space to receive a coil spring, said cylinder and core having co-operating longitudinal slots to receive a looped fastening wire.
11. A mandrel for wiring a formed coil spring comprising a hollow cylindrical portion formed to fit the spring and having a longitudinal slot in its interior surface adapted to receive a fastening wire.
12. In an apparatus for wiring a coil spring, a support, a cylindrical mandrel carrying in predetermined relation a formed coil spring and a fixed fastening wire loop having projecting ends, a rotary head having means for engaging the wire ends, and means for rotating the head to twist the wire on the spring.
13. Apparatus for twisting a formed coil spring holding wire comprising a mandrel support, a hollow cylindrical mandrel adapted to carry within itself a formed coil spring and a fixed wire loop disposed on each side of the coil with ends projecting beyond the mandrel, a reciprocatory and rotatable twisting head having its axis located in line with the coil, and means for reciprocating the head to engage and disengage the loop ends and for rotating the head to twist the loop ends while the loop and coil spring are held in fixed relation by the mandrel.

In testimony whereof I have signed my name to this specification, in the presence of two subscribing witnesses, this 31st day of October, 1917.

FREDERICK M. STEVENS.
